O. J. GASAU.
WIRE MATTRESS FABRIC.
APPLICATION FILED JULY 23, 1920.

1,373,233.

Patented Mar. 29, 1921.

Inventor
OTTO J. GASAU

By his Attorney

Chas. C. Gill

UNITED STATES PATENT OFFICE.

OTTO J. GASAU, OF BROOKLYN, NEW YORK, ASSIGNOR TO GASAU-THOMPSON COMPANY, INC., OF BROOKLYN, NEW YORK, A CORPORATION OF NEW YORK.

WIRE MATTRESS FABRIC.

1,373,233.

Specification of Letters Patent. Patented Mar. 29, 1921.

Application filed July 23, 1920. Serial No. 398,334.

To all whom it may concern:

Be it known that I, Otto J. GASAU, a citizen of the United States, and a resident of Brooklyn, in the county of Kings and State 5 of New York, have invented certain new and useful Improvements in Wire Mattress Fabrics, of which the following is a specification.

The invention pertains to wire fabrics of 10 a character specially adapted for use in connection with wire spring mattresses, and it consists in the novel structure and features hereinafter described, and particularly pointed out in the claims.

15 The fabric of my invention will be connected to the customary frames employed in the manufacture of what are termed three and five-piece bedsteads, and these 20 need not be specifically shown and described in this application.

The fabric of my invention comprises a 25 series of narrow links of double loop formation extending end to end and interlocked with one another lengthwise of the 30 fabric, and short transverse single links connecting the longitudinal double links so as to produce a fabric composed of the assembled links. Each of the longitudinal 35 links is of double formation and formed from a single piece of wire, one end of the link being bent into return double hook shape and the other end of the link being formed by twisting the ends of the wire, 40 from which the link is formed, together and bending the same inwardly or toward the hook at the other end of the link, the twisted ends of the wire forming a longitudinal member and creating recesses at opposite 45 sides thereof to receive the hooked side members of the next adjacent link, whereby the several links become very securely interengaged.

The object of my invention is to provide 45 a fabric composed of easily produced units capable of being readily assembled, and which fabric shall be capable of properly supporting the mattress of hair or the like and resisting sagging action to a requisite 50 degree.

The invention will be fully understood

from the detailed description hereinafter presented, reference being had to the accompanying drawings, in which:

Figure 1 is a top view, partly broken 55 away, of a wire mattress embodying the features of my invention;

Fig. 2 is a side elevation of two of the longitudinal links detached from the fabric; and

Fig. 3 is a transverse section, partly broken away through a portion of the fabric, taken on the dotted line 3—3 of Fig. 1.

The wire fabric is connected at its ends by helicals 10 to end rails 11 and at its 65 sides by links 12 with side members of suitable type 13 whose ends are connected by helicals 14 with the aforesaid end rails 11.

My invention pertains more particularly to the wire fabric, and this fabric will be 70 connected with the usual types of frames employed by manufacturers of wire mattresses and intended for application to or connection with the usual framing of bedsteads, such as the side bars or head and 75 foot frames thereof.

The wire mattress of my invention comprises a fabric consisting of a series of end to end longitudinal links 15 and short transverse connecting links 16, the links 15 all 80 being hooked together in longitudinal series and the links 16 being connected with and connecting the rows of links 15.

The links 15 are all alike, and each is formed from one continuous rod of wire 85 folded to form substantially parallel sides 17, 17 constituting an elongated longitudinal double-strand link, and said rod of wire at the closed end of the link or where the wire is doubled over, is bent inwardly to 90 form a substantial hook 18, while at the other end of the link the free ends of the rod of wire are brought together on curved lines and twisted upon each other to form a twisted end or arm 19 which extends centrally and longitudinally of the links and also inwardly or toward the hooks 18. The hooks 18 are of the same width as the links 15 at the ends thereof adjacent to the hooks, and the twisted ends or arms 19 at the opposite ends of the links constitute hooks and 95 create at the sides thereof pockets or recesses 100

20 located between the sides of said arms and the adjacent sides of the link. The pockets or recesses 20 at the opposite sides of the arms 19 are adapted to receive the 5 hooks 18 of the adjacent links in longitudinal series, each arm 19 then extending through the outer end of the adjacent link in series, and the hook 18 of said adjacent link passing over said arm 19 and at its 10 sides being seated in the recesses or pockets 20 formed at the sides of the arm 19. The side members 17 of each link 15, while substantially parallel, do diverge toward the end of the link having the arm 19, as clearly 15 shown in Fig. 1, and this divergence of said side members 17 results in the end of the link, possessing the arm 19, being of sufficient width to afford the pockets or recesses 20 for the hook end of the next adjacent 20 link which, by being slightly narrower, may pass over the arm 19 and become seated within said recesses or pockets. The outer row of links 15 are, by means of the hooks 18, engaged with the helicals 10, and the side links 25 15 at their inner ends are connected by the links 12 with the edge members 13, the links 12 being short rods of wire hooked over at their ends to engage the links and said edge members. The links 15 are hooked together 30 along longitudinal rows or series which are parallel with one another, as shown in Fig. 1, and said rows of links are connected together by transverse links 16, each of which is formed from a short rod of wire hooked 35 over at its ends and at one end engaging an outer link 15 of one row and at its inner end the next inner link of an adjacent row, said links 16 thus serving to more effectually connect the rows of links and in maintaining 40 their predetermined positions.

The manner of constructing the links 15 and 16 and of the assembly of these links is apparent from an inspection of the drawings. The links 15 are elongated and their 45 sides are closely related, and said links, by reason of their hook-ends, may be readily assembled and, when assembled, are capable of resisting severe strains without undue sagging. The links 15 may be readily constructed, each being formed from a single 50 rod of wire doubled upon itself and having its ends twisted together. The fabric as a whole is of desirable character for use in supporting the mattress of the bed and is

both durable and comparatively inexpensive 55 of production.

What I claim as my invention and desire to secure by Letters Patent is—

1. A wire mattress fabric comprising a series of transverse rows of spaced-apart longitudinally elongated links of double-loop formation connected together in end-to-end longitudinal series and short transverse links connecting the adjacent longitudinal links to form a complete fabric, said longitudinal links each being formed from a single rod of wire folded at about its middle portion to form a closed end and separated side members for the link and at its free ends being brought together to form a central arm which is bent inwardly to form a hook, leaving pockets between its sides and the adjacent sides of the link, and the said closed end of the link being narrower than the other end thereof and bent over to form 75 a hook, said elongated links being connected together in longitudinal series by the narrower hook-ends of one transverse row thereof being hooked over the said arms and engaged with said pockets of the links 80 of the next adjacent row.

2. A wire matress fabric comprising a series of transverse rows of spaced-apart longitudinally elongated links of double-loop formation connected together in end-to-end 85 longitudinal series and short transverse links connecting the adjacent longitudinal links to form a complete fabric, said longitudinal links each being formed from a single rod of wire folded at about its middle 90 portion to form a closed end and separated side members for the link and at its free ends being brought inwardly on curved lines and twisted together to form an arm which is extended inwardly to create a hook and 95 leave pockets at the base of its opposite sides, and the said closed end of the link being narrower than the other end thereof and bent over to form a hook, said elongated links being connected together in longitudinal series by the narrower hook-ends of one 100 transverse row thereof being hooked over the said arms and engaged with said pockets of the links of the next adjacent row.

Signed at Brooklyn, in the county of 105 Kings and State of New York, this 8th day of July, A. D. 1920.

OTTO J. GASAU.
